UNITED STATES PATENT OFFICE

FRED A. HAHN, OF EAST MOLINE, ILLINOIS

WASHING DEVICE

Application filed July 19, 1929. Serial No. 379,495.

The object of this, my present invention, is the provision of a simple, cheap but thoroughly effective device for washing fine lingerie, curtains, sheer silk hosiery and the like in a thorough and efficient manner and without danger of inflicting injury thereto.

A further object is the provision of a washing device for this purpose that includes a compressible cup-shaped member which is preferably of rubber, which has at its top a socket for the reception of a handle, its bottom formed with an inwardly extending flange and an outwardly projecting bead and its body, in a line with the bead provided with a continuous series of spaced downwardly inclined apertures that afford passages for air, suds and water when the device is operated to produce a suction as well as a soft pounding action upon the clothes being washed.

To the attainment of the foregoing the invention consists in the improvement herein-after described and definitely claimed.

In the drawings:

25 Figure 1 is a perspective view of my improvement.

Figure 2 is a substantially central sectional view therethrough.

30 Figure 3 is a top plan view thereof, the stick being in section.

In general appearance my improved washing device resembles that of an ordinary rubber plunger, the same comprising a cup-shaped body 1 of strong but compressible rubber. The body 1 is formed at its top with a central tubular extension in the nature of a socket 2 in which is received the stick or handle 3. The body 1 has the outer surface of its mouth flat and the same is formed 35 with an inwardly directed ring flange 4 and with an outwardly directed bead 5. The body 1, at its juncture with the bead 5 and the flange 4 is materially thickened to reinforce and strengthen the same, and to render the flat surface of the cup practically non-yieldable. The end of the flange 4, however, is of a thickness approximately equaling that of the rubber body and is susceptible to a slight inward yielding. The body, above the flange 40 and bead is provided with a series of annu-

larly arranged spaced openings 7 and the walls provided by these openings are inclined downwardly.

The improvement it will be noted includes no metal parts, and the top proper or the cup-like body 1 is closed to provide a wall which limits the movement of the pounding stick in the socket. The compressible socket will effectively hold the stick therein. The device is operated by a slight pounding and compression. This will create a suction which will partly draw the clothes into the cup and which will also force the water and suds through the angularly arranged openings 7 and will likewise eject air through the improvement. The suds and air, together with the suction created by the compression of the member 1 on the clothes will tend to quickly clean the same without liability of injury thereto. By reinforcing and strengthening the mouth of the device to render the same practically non-yieldable the body thereof upon the reciprocation of the handle will yield under pressure and expand when such pressure is released so that the action of the improvement is similar to that of a flexible piston. By having the openings 7 arranged angularly the water or saponaceous fluid which is sucked into the cup will be forced downwardly therethrough when the body is compressed, so that this fluid will act directly upon the clothes below the device to remove dirt therefrom and clean the same in a better and more expeditious manner than were the openings arranged at a right angle with respect to the longitudinal plane of the improvement. The device can inflict no injury to the clothes but incident to the yieldability to the edge of the flange 4 the flat mouth will firmly engage with the clothes when the device is in operation. The device is of an extremely simple nature and will not scratch or mar the finish of porcelain or granite when the same is employed in wash basins, bath tubs or the like, it, of course, being understood that the device may be employed in any type of container for soapy water and which is large enough to receive fine fabric clothes to be washed therein.

Having described the invention, I claim:

A washing device for the purpose set forth comprising a cup-shaped body of strong but compressible rubber, said body having the outer surface of its mouth flat and provided with an inwardly extending flange and an outwardly projecting bead, the body at the juncture of the bead or flange being thickened to render the beaded portion of the mouth practically non-yieldable and to permit of the inward yielding of the edge of the flange, said body above the flange and bead being provided with an annular series of openings whose walls are inclined downwardly, and a socket extension formed on the top of the body for the reception of an operating stick.

In testimony whereof I affix my signature.
FRED A. HAHN.
